VACUUM SEALING MACHINE FOR BOTTLES,
JARS, CANS, AND THE LIKE

Frank Oscar Levi Chorlton, Bury, England

Application September 30, 1932, Serial No. 635,630,
and in Great Britain October 16, 1931

3 Claims. (Cl. 226—82)

Improvements relating to vacuum sealing machines for bottles, jars, cans and the like.

The invention relates to machines employed for the sealing of bottles, cans or other like vessels, under a vacuum or partial vacuum, in a sealing chamber and known as vacuum sealing machines.

As the heights of the vessels operated upon in practice vary, adjustments are necessary in distances and movements of parts involved relatively to what is called the sealing chamber.

The invention relates to that type of vacuum machine in which a table below the sealing chamber named is provided upon which the vessel to be sealed is placed. This table is capable of an up-and-down movement within an outer cylinder termed an antechamber, or sealing cylinder, the latter being capable of sliding within an outer support. The support referred to may be clamped or attached to the framing of the machine in an adjustable manner, and this support may be conveniently termed a table-bracket as a consequence.

The object of the invention is to provide means whereby the lift of the sealing cylinder is automatically adjusted with the adjustment of the table bracket below the sealing chamber.

For this purpose, I provide mechanism in connection with the sealing cylinder named and the table-bracket, operating through leverage of a variable nature; that is to say, said mechanism has motion given to it from a suitably moving part, which motion transmitted to the sealing cylinder varies according to the height at which the table bracket is clamped, which is determined by the height of the vessel to be operated upon.

With reference to the accompanying drawings, Fig. 1 is a sectional elevation of a portion of a vacuum sealing machine adopted according to one form of my present invention. Fig. 2 is a similar view, but showing the disposition of parts when a vessel having a different height to the one previously provided for is accommodated. Fig. 3 shows a detail relative to the foregoing figures. Fig. 4 shows parts of Fig. 2, with an additional detail therein. Fig. 5 shows in elevation, and on a reduced scale, the main parts of a vacuum sealing machine arranged according to my invention. Fig. 6 is a sectional plan of a portion or detail in Figs. 1 and 2.

According to my invention, a multi-legged device or bellcrank lever 1 is shown pivoted at 2 to the table-bracket 3, the latter being clamped to the machine framing at 4. In Fig. 4 the means whereby the table-bracket is so clamped is indi-

cated. That is to say, studs 4_x are passed through a slot 3_x in said bracket for the purpose in manner well understood.

One arm of the bell-crank lever 1 is shown connected to the sealing cylinder 5 by means of a connecting link (or links) 6. The latter passes through a slot 6_x in the table-bracket 3.

The other arm of said lever device 1 is shown being impinged against by a bowl 7 revolvably mounted on a rod or member 8 sliding in bearings on the frame 4, and capable of a longitudinal movement due to a contacting cam 9 receiving motion from a revolving shaft 10, the latter being driven by horizontal shaft 10_x (Fig. 5), the two shafts being capable of being geared together for the purpose. A fast pulley 10_y for belt driving of shaft 10_x is attached to the latter.

A pivot or axis for the bell-crank lever 1 is here provided by a pin 2 having an eccentric part 2_x, and supported by a boss in connection with the table brackets. That is to say, and referring to Fig. 6, the thicker or eccentric part 2_x of the pin ends 2 is normally fixed in position by means of the pinch screws 14 in manner indicated, but when it is desired to adjust the lever 1 relatively to its mount or pin-part 2_x, the pinch screws are temporarily released. The whole of the pin 2, 2_x, may then be rotated to a desirable extent in the bracket 3, and the said screws 14 tightened again. The purpose of the eccentrically adjustable pivot for the lever 1 is to provide a means of adjusting to a limited extent the travel or lift of the sealing cylinder 5 to ensure that it makes an air-tight joint on the underside of the sealing chamber 11.

It will be seen from Fig. 1 that when the table bracket 3 has been clamped at the correct height relatively to the sealing chamber shown at 11 (and between which chamber and a table at 12 the vessel 13 is situated) the movable rod 8 is capable of pushing the adjacent arm of the bell-crank 1 to an extent suitable for raising the sealing cylinder 5 until its upper edge makes contact with the underside of the chamber 11 in an air-tight manner, as requisite. The movement of the table 12 is provided for according to known means. That is to say, and referring to Fig. 5, a spindle 12_x connected to the table 12, is impinged against by a two-armed lever 15 operated by a slidable push rod 16, the latter actuated by a cam 17, attached to shaft 10 aforesaid. It will be evident that if the spindle 12_x is made adjustable in length in any well known manner, then said spindle may be adapted to different positions of the bracket 3 relatively thereto.

The vessel shown in Fig. 1 is of a different height from the vessel 13 shown in Fig. 2, the accommodating of the latter necessitating the lowering of the table bracket 3 relatively to the framing 4, and sealing chamber 11. But it will be seen that said downward movement of the bracket named automatically brings the bowl 7 of push rod 8 at a higher level on the adjacent arm of device 1, which means that the leverage is varied or the effective length of the right-hand lever-leg relatively to the lever leg connected to link 6 is so adjusted that the greater movement of antechamber 5 now required is thus provided for.

10 In this manner is the movement of the sealing cylinder 5 adjusted as required.

I claim:

1. For a vacuum sealing machine for sealing bottles, jars, cans and the like, a table bracket 20 adjustably attachable to the machine framing, a movable sealing cylinder slidably mounted in said table bracket, a multi-legged lever device pivoted on said table bracket, a leg of said lever-device connected to said sealing cylinder and whereby the latter is moved, a reciprocally movable member mounted in bearings in said machine frame, for moving said lever leg about its pivot, a second leg of said lever device in contact with said member, and so that the distance 30 between said contact and the pivot of the lever device automatically varies when the position of the table bracket is changed on the machine frame, for the purpose and as herein set forth.

2. For a vacuum sealing machine for sealing 35 bottles, jars, cans and the like, a table bracket

adjustably attachable to the machine framing, a movable sealing cylinder slidably mounted in said table bracket, a bell-crank lever pivoted on said table bracket, a leg of said bell-crank lever connected to said sealing cylinder and whereby the latter is moved, a reciprocally movable push-rod mounted in bearings in said machine frame, for moving said bell-crank lever about its pivot, a second leg of said bell-crank lever in contact with said push-rod, and so that the distance between said contact and the pivot of the bell-crank lever automatically varies when the position of the table bracket is changed on the machine frame, for the purpose and as herein set forth.

3. For a vacuum sealing machine, for sealing bottles, jars, cans and the like, a table-bracket adjustably attachable to the machine framing, a movable sealing cylinder slidably mounted in said table bracket, a bell-crank lever pivoted on said table-bracket, a leg of said bell-crank lever connected to said sealing cylinder and whereby the latter is moved, a reciprocally movable push-rod mounted in bearings in said machine framing for moving said bell-crank lever about its pivot, a second leg of said bell-crank lever in contact with said push-rod, and so that the distance between said contact and the pivot of the bell-crank lever automatically varies when the position of the table-bracket is changed on the machine framing aforesaid, driven mechanism in connection with said push-rod and for operating the same, all for the purpose and as herein set forth.

FRANK OSCAR LEVI CHORLTON.
